UNITED STATES PATENT OFFICE

2,529,133

JUNCTION BOX

Harold L. Bush, North Syracuse, N. Y., assignor
to Crouse-Hinds Company, Syracuse, N. Y., a
corporation of New York

Application October 1, 1947, Serial No. 777,219

5 Claims. (Cl. 174—59)

1

This invention has to do with a junction box for electrical conductors and particularly an explosion proof junction box wherein branch circuit conductors are taken off from feed circuit conductors, the latter consisting of conductors of unusually large cross section.

The invention has as an object a junction box of the type referred to embodying a structure whereby the branch circuit conductors can be quickly and conveniently connected to the heavy feed circuit conductors, the connector terminals being readily adapted for various sizes of conductors, both on the branch and feed circuits.

The invention consists in the novel features and in the combinations and constructions hereinafter set forth and claimed.

In describing this invention, reference is had to the accompanying drawings in which like characters designate corresponding parts in all the views.

Figure 1 is a vertical sectional view of a junction box embodying my invention.

Figure 2 is a top plan view of the structure shown in Figure 1 with the closure cap removed and a portion of the top insulating shield broken away.

Figure 3 is a top plan view of one of the feed conductor terminal blocks.

The invention consists of a metallic housing 9 formed with apertured hubs 10, 11, to receive 30 conduits enclosing the conductors. The housing is provided with an opening in the top wall thereof which, in the structure illustrated in the drawings, is commensurate in size to the interior of the housing 9. In this case, the housing is of cylindrical form, and the opening is internally threaded to receive an inverted cup-shaped closure cap 12 which, when threaded into the opening, forms a flame tight closure for the opening.

A plurality of feed conductor terminal blocks 13 are mounted in the housing on the base wall 14 thereof, the blocks being mounted upon an insulating panel 15 secured to the bottom wall of the housing, as by screws 16, and the blocks 13 are secured to the panel in either one of two positions by screws 17 shown in dotted outline, Figure 1. The blocks 13 are formed with a transversely extending rectangular groove 18, and with a groove 19 of V formation extending at right angles to the groove 18. The corner portions of the blocks are provided with threaded apertures 20 to receive the mounting screws 17.

A terminal bar 22 is mounted upon each of the blocks 13 and extends upwardly therefrom and outwardly through the opening in the top of the

2

housing. The lower end of each of the bars 22 is formed with a jaw portion 24 adapted to be positioned in the grooves 18, 19, the bars being detachably secured to the blocks by tightening means in the form of screws 26 which also thread into the apertures 20 of the blocks 13. The jaws 24, in conjunction with the blocks 13 and the tightening means 26, form a clamp for clamping the large feed conductors 28. Branch conductor terminals 29 are mounted upon opposite sides of the bars 22 on the outwardly extending portions thereof.

With this arrangement, the housing is mounted upon the wall, or other surface, by bolts, lag screws, or the like, extending through apertured feet 31. The conduit lines are attached to the hubs 10, 11, and the conductors pulled through the conduits.

The feed conductors 28 are of large size ranging from 1/0 to 500 circular mills. To connect these heavy conductors, it is only necessary to de-insulate a short portion of each conductor and drop it into one of the connector blocks 13. The terminal bars 22 are then secured to the blocks respectively, and this operation results in the heavy conductor being clamped between the block and its associated connector bar 22.

The branch circuit conductors may be then conveniently attached to the terminals 29 inasmuch as they are fully exposed outside of the housing. These branch conductors may range in size from No. 14 wire to 4/0 wire. However, there is no difficulty in connecting the larger size branch conductors inasmuch as the branch connectors are positioned outside of the housing and the workman is in no way hampered, or obstructed, in making the connections. After the branch circuit conductors have been attached to the terminals 29, the closure cap 12 is screwed into position.

An insulating plate 36 may be detachably mounted over the ends of the terminal bars 22. As shown, blocks 37 of insulating material are detachably secured to the two outer terminal bars, as by screws 38, and the top plate 36 secured to the blocks 37, as by screws 40. Shields 41 may be mounted on the under side of the plate 36 to effectively prevent any arcing or short circuit between the terminal bars and likewise, a U-shaped shield 43 may be employed in connection with the mounting of one or more of the blocks 13.

In Figure 1, the left and center terminal block 13 is positioned to receive the feed conductors 28 in the V slots 19. The right hand block is positioned to receive the conductor in the rectan-

gular slot 18. This slot is to accommodate conductors of the smaller sizes, while the slots 19 accommodate conductors of larger size.

What I claim is:

1. An explosion proof junction box for electrical conductors comprising a housing formed with conduit receiving apertures and having an opening in the top wall, a plurality of feed conductor terminal blocks mounted in the housing on the bottom wall thereof, a terminal bar detachably secured to each of said terminal blocks and extending outwardly through said opening, the lower ends of said bars being cooperable with said terminal blocks respectively to clamp conductors thereto, branch terminal connectors carried on the outer ends of said bars, and a closure cap enclosing the outwardly extending portions of said bars and forming a flame tight closure for said opening.

2. An explosion proof junction box for electrical conductors comprising a housing for conduit receiving apertures and having an opening in the top wall, a plurality of terminal blocks mounted in the housing on the bottom wall thereof, a terminal bar extending outwardly from each of said blocks through said opening, and said bars being provided at their outer ends with branch terminal connectors, the lower ends of said terminal bars and said blocks forming conductor clamp jaws, means operable to detachably secure the terminal bars to said blocks respectively, and to contract said clamp jaws on a conductor, a closure cap enclosing the outwardly extending portions of said bars and forming a flame tight closure for said opening.

3. An explosion proof junction box for electrical conductors comprising a housing formed with conduit receiving apertures and having an opening in the top wall thereof, a plurality of feed conductor terminal blocks mounted in the housing on the bottom wall thereof, a terminal bar extending outwardly from each of said blocks through said opening and being provided at their outer ends with branch terminal connectors, the lower end of each terminal bar having a jaw member cooperable with said block in one relation to form a clamp for a feed conductor, and in another relation to form a clamp for a conductor of different size, means operable to detachably secure the terminal bars to said blocks respectively, and to move said jaw into conductor clamp-

ing position, a closure cap enclosing the outwardly extending portion of said bars and forming a flame tight closure for said opening.

4. An explosion proof junction box for electrical conductors comprising a housing formed with conduit receiving apertures and having an opening in the top wall, a plurality of feed conductor terminal blocks mounted in the housing on the bottom wall thereof, a terminal bar extending outwardly from each of said blocks through said opening and being provided at its outer end with branch terminal connectors, each of said bars having a jaw member which, in conjunction with its associated terminal block and tightening means, forms a clamp for a feed conductor, a closure cap enclosing the outer portion of said bars and forming a flame tight closure for said opening.

5. An explosion proof junction box for electrical conductors comprising a housing formed with conduit receiving apertures and having an opening in the top wall thereof substantially commensurate with the interior of the housing, a plurality of U-shaped terminal blocks mounted in the housing on the bottom wall thereof, a branch terminal bar extending outwardly from each of said blocks through said opening and being provided at its outer end with branch terminal connectors, each of said terminal bars being formed at its lower end with a conductor clamp jaw mounted between the leg portions of said U shaped terminal block, means operable to detachably secure the terminal bar to the block and to cause said jaw to clamp a feed conductor to the block, a closure cap enclosing the upwardly extending portions of said terminal bars and forming a flame tight closure for said opening.

HAROLD L. BUSH.
